AUTOMATIC HEATING PLANT

Virginius M. Cruikshank, Shamokin, Pa.

Application July 21, 1933, Serial No. 681,477

12 Claims. (Cl. 110—165)

This invention relates to heating plants and broadly aims to provide a completely automatic heating plant for burning coal or other similar solid fuels and which plant combines in a single sealed housing or enclosure, a fuel reservoir or magazine which is adapted to be directly charged by the fuel dealer at a point exterior of the building in which the plant is located, the reservoir being of such capacity as to require charging only at such intervals as the average consumer purchases a supply of fuel, the housing also containing a furnace including a boiler and a fire bed to which the fuel is automatically supplied from the reservoir and upon which the fuel is burned, together with an ash storage compartment accommodating removable receivers, the capacity of which are such as not to require any attention between the periods of the usual refuse collection, together with means also located within said housing for receiving and automatically conveying the ashes discharged from the fire bed to the receivers in the ash storage compartment.

The invention, in addition to residing in the novel construction, arrangement and combination of the foregoing elements to provide a compact entity or unitary structure, contemplates a novel form of boiler by virtue of which a greatly increased efficiency is derived proportionate to the fuel consumed, while a portion of the boiler structure functions in the capacity of a water jacketed fuel chute or reservoir outlet adjacent the point of supply of fuel to the fire bed.

The invention further resides in the novel manner of supporting the boiler so that the same is disposed above an ash receiving platform or table, thereby affording a clearance space between the upper surface of said platform or table and the bottom of the boiler to admit of the movement over said surface of an annularly movable device which functions to simultaneously direct and convey the ashes radially outward over said surface and to sweep the same therefrom through circumferentially spaced spill openings in the platform or table, into suitable ash receivers positioned thereunder and which ash receivers are located outside of the usual ash pit zone.

The invention further embraces a dewatering arrangement within the fuel reservoir, by virtue of which excessive moisture is effectually intercepted, drained off and conveyed away from the fuel supply in the reservoir to prevent any material quantity of the same from being conveyed to the fire bed.

The invention also embodies an arrangement for venting the fuel reservoir so as to admit fresh

air thereto from a point exterior of the building to supply, either through the medium of a blower or otherwise, air to the burner to promote proper combustion and draft, the arrangement being such as to also allow for the withdrawal from the reservoir of any accumulation of gas therein and conveyance of such gases with the air supply for discharge from the reservoir, either to the burner for consumption, or to any point of disposal desired so as to avoid any possible hazard of gas explosion within the reservoir.

The invention further aims to provide a heating plant of the character set forth which is comparatively simple and not complicated in its construction or mode of operation, which is capable of being economically produced, installed and maintained in working condition and which is highly efficient for its intended purpose.

With the above enumerated and other more detailed objects in view, which are hereinafter set forth, reference is now made to the following specification and accompanying drawings in which there are disclosed several embodiments of the invention, while the appended claims embrace other variations which properly fall within their scope.

In the drawings:

Fig. 1 is a front view of a heating plant constructed in accordance with the invention.

Fig. 2 is a vertical sectional view therethrough on a larger scale.

Fig. 3 is a horizontal sectional view taken approximately on a plane indicated by the line 3—3 of Fig. 2.

Fig. 4 is a detail sectional view taken approximately on the line 4—4 of Fig. 2.

Fig. 5 is a fragmentary front view of the furnace illustrating the fire doorway.

Fig. 6 is a detail plan view of the upper annulus of the clean-out means for the lower flue chamber.

Fig. 7 is a similar view of the lower annulus.

Fig. 8 is an enlarged fragmentary sectional view showing the clean-out means in opened condition.

Fig. 9 is a similar view showing the clean-out means in closed condition.

Fig. 10 is an enlarged detail fragmentary sectional view illustrating the ash remover.

Fig. 11 is a fragmentary plan view thereof.

Fig. 12 is a detail sectional view taken approximately on the line 12—12 of Fig. 10.

Fig. 13 is a fragmentary sectional plan view illustrating an alternate form of the ash remover means and an alternate form of the removable burner unit support.

Referring to the drawings by characters of reference, A designates generally the heating plant which preferably includes an independent housing made up of a continuous vertical wall 15 which, in the present instance, is disclosed as cylindrical although the shape may be varied, a bottom wall 16 and a top wall 17, the housing being of a size and proportion to be accommodated by the average cellar or other room within which the heating plant is to be located. The housing is provided with a main doorway 18 closed by a door 19, and supplemental doorways 20 closed by doors 21 by virtue of which access is gained to the interior of the housing. Within the housing is located a furnace which is designated generally by the reference character B, a fuel reservoir or magazine, designated generally by the reference character C, and an ash storage compartment, designated generally by the reference character D, the housing having a fuel charging opening 22 in the side and adjacent the top from which there leads outwardly a conduit 23 extending through an opening E in the wall F of the cellar or room 25 within which the heating plant is located, said conduit 23 having a door or closure 24 through which the fuel reservoir may be charged or supplied with fuel from a point exterior the building. The closure or door 24 is also provided 30 with vent openings 25, the purpose of which is hereafter explained.

A horizontal platform or table 26 is arranged in the lower part of the housing and spaced above the bottom 16, and which, in the present instance, is shown in the form of a partition which extends throughout the entire area of the housing, although it is not essential to the present invention that it be in this form.

The platform, table or partition 26, as illustrated, is supported by legs 27 and the partition is provided with a central portion 28 which is displaceable to gain access upwardly therethrough to mechanism located thereabove or when said portion is removed to permit of the emplacement 45 of an emergency grate. The central portion may also be displaced in the event of failure of the ash remover means so that the ash receptacle may be located directly under the fire bed whereby the ashes may directly fall in the said receptacle. The outer portion of the platform, table or partition 26, which extends beyond the legs, defines together with the bottom 16 of the housing and wall 15, an ash storage space and said portion is provided with a plurality of circumferentially spaced spill openings 29. Within the ash storage space D which is thus defined, the ash receivers 30 are adapted to be arranged, one under each of the spill openings and access is gained to said receivers through the main door 19 50 and the supplemental doors 21. In emplacing or removing the ash receivers, the rearmost one is inserted or withdrawn by direct fore and aft movement through the main front door and between the legs or supports 27. The two receivers located adjacent the rearmost one are preferably connected by a hook or some suitable form of coupling means to the next adjacent forward receiver so that each of said pairs are emplaced or removed together. In order to facilitate the 55 emplacement and removal of the ones next to the rearmost, curved guides 31 are provided. It is, of course, obvious that the outermost receiver and the two next to it may be readily emplaced or removed through the main and supplemental doorways.

The furnace B includes a boiler which comprises vertically spaced and aligned upper and lower, substantially annular, headers designated generally by the reference characters 32 and 33, and fire and water tubes 34 and 35 connecting said headers. The fire tubes 34 extend through the water tubes and the headers from the upper wall or tube sheet 36 of the upper header to the lower wall or tube sheet 37 of the lower header through which walls or tube sheets said fire tubes open. The water tubes 35 extend from the lower wall or tube sheet 38 of the upper header to the upper wall or tube sheet 39 of the lower header and open therethrough to establish communication between the headers. As shown, the relative diameter of the fire and water tubes are such as to define therebetween annular water legs extending between the headers by means of which the columns of water contained therein are rapidly heated. The outer wall 40 of the upper header is annular or cylindrical while the inner wall is fashioned to provide a depending funnel shaped fuel feed hopper 41 for directing the fuel therethrough for discharge into a fire bed therebelow and within the combustion chamber 42 defined by the headers and water tubes. The inner wall of the upper header which defines the fuel feed hopper 41, comprises inner and outer upwardly and outwardly divergent funnel shaped portions 43 and 44 which are joined 30 at the upper ends respectively to the upper and lower walls or tubes sheets 36 and 38 of the upper header 32 and which portions 43 and 44 are joined together at their lower ends so that the fuel feed hopper 41 is water-backed or water-jacketed.

The furnace also includes a substantially cylindrical baffle 45 which extends upwardly from the lower header, surrounding the water tubes and terminating at a point spaced below the lower wall or tube sheet of the upper header. The furnace further includes an outer cylindrical shell 46 which is spaced from the headers and baffle, with the upper end of said outer shell disposed in substantially the same plane with the upper wall or tube sheet of the upper header and with the lower end of said outer shell extending below the lower wall or tube sheet 37 of the lower header. A wall 47 extends downwardly from the lower inner corner of the lower header 50 and the lower edge terminates in a plane coincident with the lower end of the outer shell 46. Means, which is hereinafter described in more detail, extends between the lower end of the shell 46 and the wall 47 to define a lower annular flue 55 chamber 48 with which the fire tubes 34 communicate and into which opens the lower end of an annular flue space 49 defined between the baffle 45 and the outer shell 46. The furnace is completed by an upper annular flue chamber 50 60 which is defined in part by the upper wall or tube sheet 36 of the upper header and by a wall section 51 which bridges the space between the upper header and the outer shell 46. The upper flue chamber 50 is further defined by a funnel shaped inner wall 52 which extends from the upper inner edge of the upper wall or tube sheet 36, upwardly and outwardly to an annular side wall 53, the funnel shaped wall 52 opening into the upper end of the fuel feed hopper 41. Obviously, as shown, the upper ends of the fire tubes open into and communicate with the upper flue chamber 50 and a flue outlet 54 is provided in the upper flue chamber from which a 75

conduit 55 leads through the housing 15 to the chimney.

The boiler and other furnace elements may be supported in any desired manner so as to dispose the lower end thereof above and in spaced relation to the upper surface of the platform, table or partition 26, but for the purposes of the present illustration which is not intended as a limitation upon the scope of the invention, said 10 elements are supported from a funnel shaped member 57 which constitutes the main hopper portion of the fuel reservoir C and the lower end of which member 57 opens into the upper portion of the funnel shaped wall 52. The purpose of 15 supporting the boiler and other furnace elements in spaced relation to and above the upper surface of the platform, table or partition 26, is to afford a clearance space to permit of the employment of means for effecting annular and radial movement of the ashes and residue beyond the confines of the furnace into the receivers provided in the ash storage space, so that room is afforded for the accommodation of a large amount of 20 ashes to avoid the necessity of frequent removal thereof. It will be observed that due to the size of the fuel reservoir, a capacity is provided which requires charging only at such intervals as the average consumer ordinarily purchases a supply 25 of fuel, inasmuch as the reservoir will, in the larger sizes, accommodate approximately four tons of fuel. It will also be observed that the consumer is not required to handle the fuel which is automatically supplied to the fire bed, either solely by gravity, as shown, or through any equivalent feed means.

The burner unit, shown in the present instance, is one of a number of types which are now in use, the one shown constituting a fire bed supporting member 60 having draft openings 61 and 40 a central unapertured portion 62 upon which a rotary impeller 63 is mounted to turn and feed the fuel radially outward at such a speed that the fuel is completely consumed by the time it reaches the outer marginal edge of the fire bed 45 member and the ashes and residue drop therefrom onto the platform, table or partition 26. The burner unit is constructed in such a manner as to define under the fire bed supporting member, a draft chamber 64 to which an air draft 50 is conveyed by a conduit 65, which leads from the outlet 66 of a blower 67 and through which a conduit extends a drive shaft 68 operatively connected with and driven by a motor 69 which also drives the blower 67. The drive shaft has a 55 driving connection with the impeller 63 at a point located within and adjacent the axial center of the draft chamber 64. The burner unit is removably supported by the furnace within the combustion chamber, in one of several ways, 60 whereby its removal or emplacement may be readily and expeditiously effected with the greatest facility. As illustrated in Figs. 3 and 4 of the drawings, the conduit 65 is formed with a casting 74 which is provided with vertical grooves 75 on its opposite sides to engage with lugs 76 on the ends of the lower header 33 at a cut-away portion thereof, while the baffle 45 and outer shell of the furnace 43 are formed with aligned inner and outer fire doorways 77 to permit of the 65 introduction of the burner head to the furnace and its removal therefrom as well as hand firing of the furnace in an emergency, as hereinafter explained. The edge of the outer doorway 77 is notched to accommodate the forward portion of the casting after its grooves 75 are seated over

the lugs 76 and when the fire door 78 is closed the furnace is sealed. Likewise, it will be noted that the fire and water tubes are eliminated adjacent the fire doorways to allow for the emplacement and removal of the burner head. In this instance, the burner head is introduced through the fire doorway and the casting 74 brought to a point where the grooves 75 are directly over and align with the lugs 76 after which the complete burner unit is lowered to slide the grooved sides 10 75 of the casting into place.

An alternate manner of introducing and supporting the burner is disclosed in Fig. 13 in which the outer shell 46 of the furnace is provided with an opening 79 below the fire doorway and the 15 burner conduit 65 extends through and has secured thereto a closure plate 80 which is bolted in position by bolts 81 to cover the opening 79 and attach and support the burner unit in place.

The ash removing means is so constructed and 20 arranged as to effect a compound translatory movement of the ashes over the surface of the platform or table and outwardly and about the furnace and boiler beyond the confines thereof 25 so as to sweep the same from such surface through the spill openings 29 into the underlying ash receivers 30 so that all of the receivers are uniformly filled. Several embodiments of the ash removal means have been illustrated by way of example and in the form shown in Figs. 2, 3, 10, 30 11 and 12, a driven rotary shaft 84 is employed which extends radially outward from a bearing 85 in a member 86 which is swiveled for free turning movement about the lower end of the impeller shaft 87 which depends from the draft 35 chamber 64. The outer end of the shaft extends to a point beyond the outer side of the spill openings and is journaled in the frame of a truck 88 which is supported by truck wheels 89 bearing on and adapted to roll over the upper surface of the 40 platform, table or partition 26, in a path outside of or beyond the spill openings 29. The shaft 84 is formed with a worm or screw conveyor blade 90 which upon turning movement, feeds the ashes outwardly as the shaft is bodily moved in an 45 annular path over the surface of the platform or table. A follower scraper blade 91 is suspended from the bight 92 of a bail, the arms 93 of which are provided with bearings 94 surrounding the shaft 84 which freely turns within the 50 bearings so that the follower scraper blade pushes and maintains the ashes to be acted upon by the conveyor. The outermost portion of the follower scraper blade is curved rearwardly adjacent its outer end as at 95 to present a concavity in its 55 forward or leading face within which the ashes are pocketed so as to facilitate the sweeping of the same from the platform or table surface through the spill openings 29, the concavity also serving to prevent the ashes from reaching that 60 portion of the surface which serves as the path for the traction wheels. The rotary driven shaft 84 imparts motion to the traction wheels 89 through the medium of a gear 96 which meshes with pinions 97 on the traction wheel axles 98. 65 It will be observed that the pitch and feed of the worm or screw conveyor blade 90 is such with reference to the direction of rotation of the shaft and translatory movement thereof that there is no tendency of obstructions to jam between the 70 outer edge of the blade and the surface of the platform or table which might interfere with the proper operation of the ash removal means. In other words, as viewed from the outer end, the shaft 84 turns in a clockwise direction while the 75

- traction wheels turn in a counter-clockwise direction due to the gearing arrangement. Due to the free pivotal mounting of the follower scraper, its lower edge engages with the upper ash receiving 5 surface gravitationally, so that in event of encountering obstruction the scraper will be lifted and ride over the same thereby avoiding jamming which might result in damage to the mechanism. Obviously, the shaft 84 may be driven in various 10 ways but in connection with a burner unit of the type illustrated, the depending portion of the shaft 87 is provided with a bevelled gear 99 which meshes with a bevelled pinion 100 secured to the inner end of the shaft 84.
- 15 The ash removal means, in its alternate form shown in Fig. 13 includes the radial shaft 84 journaled in and supported at its outer end by the wheeled truck 88 with a single driven traction wheel 89, the other wheel being in the nature of 20 an idler supporting wheel. In this instance, however, the worm or screw conveyor blade 90 is eliminated and a pusher scraper blade 101 is employed which is fashioned to present a convex curved inner portion forming a cammed impeller 25 surface, while the outer portion is reversely curved at 102 to present a concavity for pocketing the ashes. In this instance, the central portion of the blade 101 may, if desired, be supported in 30 closely spaced relation to the ash receiving surface of the platform 26, by a trailer caster roller 103 which bears on said surface of the platform or table 26.
- In order to partition off the space between the lower end of the boiler and the upper surface of 35 the platform or table 26 in so far as it is possible to do so, an annular closure member 104 is provided which rests on the platform or table and extends upwardly therefrom to bridge the space between the platform and the lower end of the 40 boiler. This seal or closure member 104 is formed with a notch 105 opening through its lower edge to provide a passage accommodating therethrough the shaft, scraper blade and other elements of the ash removal means and to afford 45 an outlet through which the ashes may pass outwardly. The seal or closure member 104 is designed to be turned with the ash removal means by radial push arms 106 which are secured to and radiate from the swiveled member 87 with the 50 outer ends of the push arms engaging with radially inwardly directed lugs 107 on the ring or annulus 104.
- In order to seal off and enclose the ash removing means, an annular wall 108 is secured to 55 and extends upwardly from the platform, table or partition 26, at a point outside of the path of movement of the truck 88 and a covering 109 is arranged thereover and extends inwardly therefrom to the outer shell 46 of the furnace. This 60 construction permits of the elimination of a portion of a continuous vertical wall 15 which lies between the partition and the upper end of the reservoir forming member 57. The covering 109 is preferably removably supported by supporting 65 means 110 on the shell 46 and is preferably made up of sections thus permitting its ready removal to gain access to the interior when desired.
- In view of the fact that coal or other similar 70 solid fuels are wetted so that the supply contains water or a considerable content of moisture which, in a large capacity gravity feed fuel reservoir will drain through the outlet, the present invention comprehends a means for intercepting and conveying off the moisture before it reaches 75 the outlet of the reservoir. This means consists

of one or more sheds, two being illustrated in the present instance, namely, an upper shed 110 and a lower shed 111. The upper shed is located within the confines of the reservoir defining member 57 and is in the nature of an inverted funnel shaped body open at its upper and lower ends and supported by radial spider arms 112. Obviously, the shed intercepts and deflects water from the main body of fuel thereabove and directs the same toward the wall of the reservoir which is provided at a point therebelow with a gutter 113, the diameter of which gutter is less than the diameter of the lower enlarged end of the shed body. Also, the gutter is canted or inclined and at the lower portion thereof communicates with a drain pipe 114. The lower shed in the present instance, is also in the form of an inverted funnel shaped body which is closed at its upper end and supported by an upwardly extending shaft 115. A lower gutter 116 is provided in close proximity 20 to the lower end of the fuel feed hopper 41 and is slightly inclined and communicates at its lowest portion with the drain pipe 117 which drain pipe together with the drain pipe 114 discharge into a common drain pipe 118. In addition to 25 performing its function as a shed, the lower member 111 also functions in the capacity of a stopper when moved downwardly into contact with the wall of the fuel feed hopper 41, as shown in dotted lines in Fig. 2, the said downward movement being effected when the shaft 115 is moved downwardly. The shaft is pivotally connected to one end of a lever 119 which lever is fulcrumed at 120 to a bearing bracket 121 secured to and depending from the top 17 of the housing. The 30 opposite end of the lever has connected therewith a manipulator rod 122 which extends through an aperture in the member 57 and is normally secured in a position to hold the shed 111 raised by engagement with a detent 123 on the inner 35 wall of the housing or upon any other suitable support.

The shaft 115 is preferably in the form of a hollow tube or pipe having a passage 124 opening through the lower end within the shed 111 and 40 extending therefrom upwardly and communicating with a flexible conduit 125 which leads outwardly of the reservoir and connects with the outlet or pressure side of the blower so as to discharge through the reservoir outlet a draft of air 45 from a point within said outlet so as to drive off gases therefrom and prevent any possibility of accumulation and explosion of the same within the fuel reservoir.

A stack 126 extends through the reservoir wall 55 member 57 and terminates adjacent the top wall 17 and is provided with a covering or protector apron 127, the lower end of the stack being connected by a conduit 128 to the blower intake to supply air thereto which is admitted through the 60 vent openings 25 in the filling door or closure 24 and at the same time effecting circulation of air in the fuel reservoir and tending to draw off any 65 gases which may accumulate therein, so that said gases are fed to the combustion chamber and consumed therein.

The lower end of the lower flue chamber is closed by suitable means which is so constructed as to permit of and facilitate periodical cleaning out of flue dust and other solid matter which 70 passes through the flue passages and gravitates into the bottom of the lower flue chamber. As illustrated, this means consists of a fixed lower annulus 130 having closely spaced circumferentially arranged openings 131 and an upper an- 75

5 nulus 132 having circumferentially arranged and spaced apertures 133, the apertures in the upper annulus being normally staggered with relation to the apertures in the lower annulus so that the bottom of the flue chamber is closed but adapted to be opened upon registration of the apertures.

In order to facilitate dislodgment of the material collected, the upper face of the upper annulus is faceted to provide the surfaces 134 which 10 incline to the openings 133 and with adjacent surfaces extending to a sharp edge or point. In order to provide means for agitating the upper annulus to effect the dislodgment of the material, the same is provided with a depending stud 135 15 which extends through one of the apertures 131 of the lower annulus and provides a manipulator which may be engaged by a suitable implement for accomplishing the agitating operation.

In order to provide means for varying the 20 tractive force of the truck wheels 89, the truck is provided with a suitable support 140 having an upstanding stud 141, and weights 142 are positioned over the stud and seated on the support 140.

25 The fuel reservoir may be equipped with an emergency reserve fuel supply which is adapted to be consumed only in event the supply in the main reservoir is completely used up before the user realizes that the reservoir needs recharging. 30 For this purpose, an emergency supply bin 150 is provided which is located within the main reservoir C and which is so arranged as to be filled, if empty, when the main reservoir is filled. The bin is open at the top and has a restricted outlet 151 35 at its lower end which is normally closed by a weighted spherical closure element 152 which gravitates to its closed position and which has connected therewith a flexible pull element or chain 153 trained around guides 154. When it is desired to render the emergency supply in the 40 bin 150 available, the flexible element 153 is utilized to draw the closure element 152 upwardly through the supply of coal in the bin and said closure element will rest on top of the supply and 45 will move downwardly therewith as the fuel supply level recedes, until the closure element again automatically closes the outlet 151.

What is claimed is:

1. In an automatic heating plant for burning 50 solid fuels, a furnace, a burner unit removably associated with said furnace and having a fire bed support located within the combustion chamber thereof and a platform having an upper ash receiving surface, said platform extending outwardly beyond the sides of the furnace and adapted to receive thereon ashes discharged from the fire bed support and a removable central portion of said platform adapted to be displaced to permit of the insertion of an emergency grate.

60 2. In an automatic heating plant for burning solid fuels, a furnace having a combustion chamber and a burner unit including a fire bed support located within the combustion chamber; a platform having an upper surface adapted to receive ashes discharged from the fire bed support, said platform having a portion extending outwardly beyond the sides of the furnace and said extended portion having circumferentially arranged spill openings, and ash removal means 65 movable in an annular path over the upper surface of said platform for simultaneously effecting the conveyance of the ashes radially outward beyond the sides of the furnace and the sweeping of the ashes from the platform through the spill 70 openings.

3. In an automatic heating plant for burning solid fuels, a furnace having a combustion chamber, a burner unit including a fire bed support located within the combustion chamber, and stoking mechanism for supplying fuel to the fire bed support; a platform having an upper surface adapted to receive ashes discharged from the fire bed support, said platform having a portion extending outwardly beyond the sides of the furnace, the extended portion of said platform having circumferentially arranged spill openings, ash removal means movable in an annular path over the upper surface of the platform for simultaneously effecting the conveyance of the ashes radially outward and the sweeping of the same from the platform through said spill openings, and means operable by said stoking mechanism for driving the ash removal means.

4. In an automatic heating plant for burning solid fuels, a furnace having a combustion chamber and a burner unit including a fire bed support located within the combustion chamber; a platform having an upper surface adapted to receive ashes discharged from the fire bed support, said platform having a portion extending outwardly beyond the sides of the furnace and said extended portion having circumferentially arranged spill openings, and ash removal means movable in an annular path over the upper surface of said platform for simultaneously effecting the conveyance of the ashes radially outward beyond the sides of the furnace and the sweeping of the ashes from the platform through the spill openings, said ash removal means comprising a driven shaft having a worm conveyor thereon, a wheeled truck to which the outer end of the shaft is journaled and gearing on the shaft and truck wheels for driving the latter to obtain traction of the wheels on the platform surface.

5. In an automatic heating plant for burning solid fuels, a furnace having a combustion chamber and a burner unit including a fire bed support located within the combustion chamber; a platform having an upper surface adapted to receive ashes discharged from the fire bed support, said platform having a portion extending outwardly beyond the sides of the furnace and said extended portion having circumferentially arranged spill openings, and ash removal means movable in an annular path over the upper surface of said platform for simultaneously effecting the conveyance of the ashes radially outward beyond the sides of the furnace and the sweeping of the ashes from the platform through the spill openings, said ash removal means comprising a driven shaft having a worm conveyor thereon, a wheeled truck to which the outer end of the shaft is journaled and gearing on the shaft and truck wheels for driving the latter to obtain traction of the wheels on the platform surface, and a follower scraper fulcrumed on the shaft and spaced therefrom.

6. In an automatic heating plant for burning solid fuels, a furnace having a combustion chamber and a burner unit including a fire bed support located within the combustion chamber; a platform having an upper surface adapted to receive ashes discharged from the fire bed support, said platform having a portion extending outwardly beyond the sides of the furnace and said extended portion having circumferentially arranged spill openings, and ash removal means movable in an annular path over the upper surface of said platform for simultaneously effecting the conveyance of the ashes radially outward

- beyond the sides of the furnace and the sweeping of the ashes from the platform through the spill openings, said ash removal means comprising a driven shaft having a worm conveyor thereon, a 5 wheeled truck to which the outer end of the shaft is journaled and gearing on the shaft and truck wheels for driving the latter to obtain traction of the wheels on the platform surface, the gearing being such as to cause the truck wheels to be 10 turned in a direction opposite to the direction of rotation of the shaft and conveyor.
7. In an automatic heating plant for burning solid fuels, a furnace having a combustion chamber and a burner unit including a fire bed support 15 located within the combustion chamber; a platform having an upper surface adapted to receive ashes discharged from the fire bed support, said platform having a portion extending outwardly beyond the sides of the furnace and said extended 20 portion having circumferentially arranged spill openings, and ash removal means movable in an annular path over the upper surface of said platform for simultaneously effecting the conveyance of the ashes radially outward beyond the 25 sides of the furnace and the sweeping of the ashes from the platform through the spill openings, said ash removal means comprising a driven shaft, a wheeled truck supporting the outer end of the shaft, the truck wheels being driven by the shaft 30 and a pusher scraper blade supported by the shaft and fashioned to present a convex curved inner portion forming a cam impeller acting upon the ashes on the surface of the platform to effect compound translatory outward and annular 35 movement thereof.
8. In a furnace for burning solid fuels, a fire bed support, means for receiving the ashes discharged from the fire bed support, and means for conveying and distributing the same successively 40 at locations spaced circumferentially about and outside of the furnace.
9. In a furnace for burning solid fuels, a fire bed support, a plurality of ash receptacles located 45 outside of the furnace and arranged circumferentially thereabout, means for receiving the ashes discharged from the fire bed support, and means for conveying and distributing the same successively to said receptacles.
10. In a furnace for burning solid fuels, an 50 automatically stoked circular fire bed support, and means for receiving the ashes discharged from the fire bed support and conveying the same

radially outward from and circumferentially with reference thereto, said means comprising a member having a horizontal ash receiving surface disposed below the upper surface of the fire bed support and extending outwardly beyond and around the outside of the furnace with circumferentially arranged spill openings therein exterior of the furnace, a removable receiver located below each spill opening, a driven radially projecting element movable in an annular path over said ash receiving surface for simultaneously conveying the ashes radially outward and for sweeping the same from said surface successively through the spill openings into the receivers. 10

11. In a furnace for burning solid fuels, an 15 automatically stoked circular fire bed support, and means for receiving the ashes discharged from the fire bed support and conveying the same radially outward from and circumferentially with reference thereto, said means comprising a member having a horizontal ash receiving surface disposed below the upper surface of the fire bed support and extending outwardly beyond and around the outside of the furnace with circumferentially arranged spill openings therein exterior of the furnace, a removable receiver located 20 below each spill opening, a driven radially projecting element movable in an annular path over said ash receiving surface for simultaneously conveying the ashes radially outward and for sweeping the same from said surface successively 25 through the spill openings into the receivers, said element having driven traction means at its outer end engaging with the upper surface of said member, and means for varying the tractive force 30 of said traction means.

12. In a furnace for burning solid fuels, a fire bed support, a furnace wall extending around and below the fire bed support, an ash platform spaced 40 below said furnace wall and extending outwardly therefrom with the protruding portion of said platform disposed in surrounding relation to the furnace, a driven ash remover travelling over said platform and extending through the space between the furnace wall and the platform for moving the ashes radially outward over the platform 45 onto the portion thereof outside of the furnace, and a sealing ring rotatable with the ash remover for closing said space, said sealing ring having a notch through which the ash remover extends and 50 through which the ashes pass.
